UNITED STATES PATENT OFFICE.

ARTHUR W. HARRISON, OF WASHINGTON, DISTRICT OF COLUMBIA, ASSIGNOR TO ISADORE BRADLEY, OF NEW HAVEN, CONNECTICUT, AND ALBERT H. FLOECKHER AND SETH A. TERRY, BOTH OF WASHINGTON, DISTRICT OF COLUMBIA.

POCKET HEAD-REST.

SPECIFICATION forming part of Letters Patent No. 394,649, dated December 18, 1888.

Application filed March 20, 1888. Serial No. 267,839. (No model.)

To all whom it may concern:

Be it known that I, ARTHUR W. HARRISON, of Washington, in the District of Columbia, have invented new and useful Improvements 5 in Pocket Head-Rests; and I do hereby declare the following to be a full, clear, and exact description of said invention, reference being had to the accompanying drawings, and to the letters or figures of reference marked 10 thereon, which form a part of this specification.

The object of my invention is to provide a simple and inexpensive head-rest which may be readily and quickly folded, so it can be 15 carried in the coat-pocket, or can be opened and slipped over the back of a car seat or chair.

My invention consists in the construction and combination of parts, as hereinafter 20 described and claimed.

In the drawings which accompany and form a part of this specification, Figure 1 is a perspective view of the device complete ready for attachment to a car-seat back. Fig. 2 is a 25 front view of the device with the rest or cushion omitted. Fig. 3 is a side view of the device, omitting the rest or cushion and showing in dotted lines the position of the legs of the device when sprung over the back of a 30 car-seat, which is also shown in dotted lines. Fig. 4 is a detail view of the rest or cushion and the brace-rod secured in a hem thereof; and Fig. 5 is a view showing the parts folded and placed in a case, the whole being ready 35 for convenient transportation, the case being of the shape such as commonly used for spectacles.

The frame of my device is composed of three parts, made, preferably, of spring-wire, 40 as phosphor-bronze or steel; but it will be understood that the material may be in other form than wire—for instance, it may be of spring metal in ribbon form. For the sake of brevity, however, I shall refer to the material as wire.

Two pieces of wire, A and A', are bent substantially alike into a form such as shown in Fig. 3. The front legs, a a', terminate in

smooth ends, and at b b' the wire is bent into shoulders, as shown. The wire is then carried upward and bent into suitable form to support the fabric or leather rest or cushion, and is thence carried downward to a point a little below the shoulders b b', where it is bent into shoulders d d'. Thus arms c c' are formed, 55 over which the fabric or leather rest is to be slipped. The wire is then bent downward, as at e e', and carried inward toward the legs a a'. These rear clamping-legs, e e', have loops or eyes f f', by which the two portions A A' are 60 hinged together, while at the same time allowing them to be laid flat against each other, and thus folded into a compact form, as shown in Fig. 5.

The brace-rod G, forming the third part of 65 the frame, is composed of a single piece of wire, and is provided with loops g g', which are adapted to slide over the arms c c' to the point under shoulders b b' and above shoulders d d', the elasticity of the side frame-wires allowing 70 this, and then the shoulders confine the rod in place. To this brace-rod is secured, by stitching or other suitable fastening means, a strip of flexible material, as leather or fabric—such as webbing—as shown at H, to form the rest 75 or cushion for the head. This rest is also provided with pockets h h' to receive the arms c c'.

The rest may be folded around the brace-rod, and with the folded side portions, A A', of the frame be slipped into a suitable envelope 80 or case, as shown in Fig. 5. The whole is therefore easily portable in a pocket or valise either with or without a case.

To arrange the device for use, the side portions, A A', are opened to allow the loops g g' 85 to slip over the arms c c'. Then by sliding the brace-rod down the pockets h h' are drawn over said arms c c', and when the rod, with its loops, has reached the point shown in the drawings the elasticity of the wires of the 90 side portions will cause the shoulders to confine said rod in position with the rest or cushion stretched taut.

The rod, with its loops, has two further functions—viz., it keeps the side portions of the 95 frame spread apart, and also confines the elas-

ticity of the clamping-legs to those portions of the wire which are below the loops.

The shoulders or horizontal portions d d' are made sufficiently long to allow for the thickness of the back of the car seat or chair to which the device is adapted; but it will be understood that for ordinary chair-backs the shoulders d d' will be made shorter and the clamping-legs will be provided with a covering of some soft material.

Instead of connecting the rear legs together, the front legs may be so united, or both front and rear legs may be hinged, or the side portions may be made in one piece and the legs bent so as to form a spring-hinge instead of the loop-hinge ff' .

It being sometimes desirable to supply cushions or rests of different kinds of material, I contemplate the manufacture and sale of the cushion, with the brace-rod attached, as a separate article of manufacture.

Having thus described my invention, what I claim is—

1. A head-rest frame consisting of two parts hinged together at one end and a brace or connecting rod having a loop at each end for holding said two parts in fixed relation to each other, substantially as described.

2. A folding head-rest consisting of two frame portions connected directly together at one end, whereby a V-shaped frame may be formed, a brace or connecting rod for holding said portions spread apart, and a rest or cushion for connecting the upper ends of said frame portions above the brace-rod, substantially as described.

3. A folding head-rest consisting of the wire frames A A' , hinged together and provided with shoulders, as shown, a brace or connecting rod provided with end loops adapted to slide over the ends of frames A A' , and a rest or cushion connected to said brace-rod and having pockets to fit over said frame ends, substantially as described.

4. In combination with a flexible rest or cushion provided with a pocket at each end, a rod secured to one edge of said cushion and extending from one pocket to the other, and provided with end loops, substantially as described.

In testimony whereof I affix my signature in presence of two subscribing witnesses.

ARTHUR W. HARRISON.
